FLEXIBLE POCKET RECEPTACLE

Douglas J. Broughton, Springfield, Mass., assignor to Buxton, Incorporated, Springfield, Mass., a corporation of Massachusetts

Application February 21, 1947, Serial No. 729,971

1 Claim. (Cl. 150—38)

1

This invention relates to an improvement in billfolds, card cases and similar flexible pocket receptacles of the type having a transverse line of fold about which one end section is folded onto the other, the coinciding edges of the end sections being provided with cooperating elements of a slide fastener by which the receptacle is held closed in folded position.

The principal object of the invention is to provide a cover and liner construction which permits a more efficient and desirable arrangement of the slide fastener members than is possible with prior constructions.

Other and further objects will be apparent from the following specification and claim.

In the accompanying drawings,

Fig. 1 is a front elevational view of a receptacle embodying the invention, the receptacle being closed;

Fig. 2 is an edge view looking from the left of Fig. 1;

Fig. 3 is a view similar to Fig. 1 but with the receptacle open;

Fig. 4 is a fragmentary detail looking from the rear of Fig. 3;

Fig. 5 is a view looking from the top of Fig. 3 the front and rear walls being spread apart; and

Fig. 6 is a fragmentary view similar to Fig. 3 showing the invention applied to a receptacle for holding pass cards or the like.

Referring to the drawings the cover of the receptacle is shown as comprising a single piece of leather, or similar material, generally indicated at 1 and a lining member 2 which, with the exception later referred to, substantially conforms in shape and dimensions to the cover. The cover, and lining are foldable about a transverse folding zone 3 to position the end sections 4 and 5 one over the other. The free edges of the end sections are provided with conventional slide fastener members 6, connected thereto by flexible tapes 7, and adapted to be brought into and out of interengagement by the usual actuating member or slider 8.

As shown in Figs. 3 and 4, wall members 9 and 10 are secured to the inner face of the end sections 4 and 5 respectively. Members 9 and 10 each includes a flap portion respectively indicated at 11 and 12, which are folded downwardly between lining 2 and members 9 and 10. An intermediate member 13 bridges the space between the inner wall end sections with its end portions telescoped between the members 9 and 10 and their respective flaps 11 and 12.

The inner edges of tapes 7 are positioned be-

2

tween the edge portions of cover 1 and lining 2 and are secured in place by a line of stitching 14 which also secures the outer and bottom edge portions of members 9 and 10, and the outer ends 5 of flaps 11 and 12, to the cover 1 and its lining 2.

Members 9, 10 and 13 combine to provide the inner wall of a bill compartment of which cover member 1 and its lining 2 forms the outer wall. The inner wall may be variously constructed and 10 may include additional pocket and purse forming members 16 and 17.

As best shown in Fig. 4 the cover member 1 is notched or recessed at the bottom of folding zone 3, as indicated at 18, to a depth approximating the 15 length of the slider 3. The corresponding portion of lining 2 is notched as at 19 only to a depth sufficient to accommodate the change in direction of the slide fastener members 6 required to permit the receptacle to open flatly when the 20 slider 3 is positioned in notch 18. The stitching 14 follows the notch 18 and as a result the portion 20 of the lining which overlies notch 18 forms a semi pocket or shield behind which the 25 major portion of slider 3 is positioned when the receptacle is open.

By this arrangement, as clearly shown in Fig. 5, bills or papers as they are placed in the bill compartment are prevented from any contact with the slider and may be neatly and quickly seated along the bottom of the compartment. 30 Since the slider may be, and preferably is, at the bottom when the billfold is open the upper edge of the rear wall is completely free of obstruction in inserting the bills in the pocket. In prior art construction it has been customary to place the 35 slide fastener so that the slider would be at the top when the billfold was open. In that position it interfered with inserting bills in the pocket but this was merely a preferable choice of evils since the interference was substantially greater when 40 the position of the slider was reversed. By my construction interference from the slider is completely eliminated, and when the receptacle is closed and fastened the slider is positioned at the top, as shown in Fig. 1, which is by far the most 45 convenient place for it in the initial steps of opening the receptacle.

While the present invention perhaps has its greatest utility in receptacles of the billfold type, 50 it also has substantial advantage in pass cases and similar receptacles where a plurality of pass carrying envelopes such as indicated at 21 in Fig. 6 are hinged to the folding zone 3 of the receptacle. As shown the envelopes 21 are hinged 55 in any usual manner, as by a blind staple 22

through the lining 2. As shown in Fig. 6 the pass envelopes may extend to the edge of the lining without interference from the slider which is positioned behind the shield forming portion 20 of the lining when the case is open.

I claim:

In a billfold of the type having end sections foldable one over the other about a transverse folding zone and having a tape supported slide fastener means for releasably connecting the opposite free edges of the sections together when folded one on the other, a cover member and a lining member stitched together adjacent their edges with the tape carrying the interengaging members of the fastener secured between the edges of the 15 cover and lining member by said stitching, front wall members secured in superposed relation on the lining member by said stitching to form a bill compartment, open along its upper edge, between the lining member and front wall members, the 20 cover member being notched at the lower end of said folding zone to receive the slider element of the fastener when the billfold is open, said lining member extending over said notch in the cover member to bridge at least that portion of the 25

notch lying above the lower edge of the front wall member at said folding zone whereby the lower edge of bills are directed by the liner to a seat at the bottom of the bill compartment without engaging the slider element of the fastener when the latter is positioned in the notch.
